(57) **CLAIM**

The ornamental design for a virtual reality head-mounted display, as shown and described.

DESCRIPTION

FIG. 1 is a front elevational view of a virtual reality head-mounted display according to one embodiment of the claimed design;

FIG. 2 is a back elevational view thereof;

FIG. 3 is a first-side elevational view thereof;

FIG. 4 is a second-side elevational view thereof;

FIG. 5 is a top plan view thereof;

FIG. 6 is a bottom plan view thereof; and,

FIG. 7 is a perspective view thereof.

Broken lines (if any) showing the environment in any figures are for illustrative purposes only and form no part of the claimed design.
